UNITED STATES PATENT OFFICE.

FRANK CONRAD, OF SWISSVALE, PENNSYLVANIA, ASSIGNOR TO WESTINGHOUSE ELECTRIC AND MANUFACTURING COMPANY, A CORPORATION OF PENNSYLVANIA.

VAPOR-ARC RECTIFIER.

1,264,276.

Specification of Letters Patent. Patented Apr. 30, 1918.

Application filed May 11, 1914. Serial No. 837,720.

To all whom it may concern:

Be it known that I, FRANK CONRAD, a citizen of the United States, and a resident of Swissvale, in the county of Allegheny and State of Pennsylvania, have invented a new and useful Improvement in Vapor-Arc Rectifiers, of which the following is a specification.

My invention relates to metallic containing receptacles for vapor arc rectifiers and more specifically to the seal between a wall of the containing receptacle and a conducting member projecting therethrough.

The object of my invention is to construct a seal of the character described that may be quickly and easily constructed and assembled; that will thoroughly insulate the conducting member from the wall of the containing receptacle, and that will maintain an air tight joint throughout a wide range of temperature changes.

In the accompanying drawing, Figure 1 is a view of my improved seal, partially in elevation and partially in section; and Fig. 2 is a fragmentary view, in section, of a modified form of the insulating bushing employed.

Referring to Fig. 1, 3 is the flat cover of the containing receptacle of a vapor arc rectifier, and is preferably a steel forging. An opening, preferably circular in outline, is cut in the cover 3 for the reception of an insulating bushing 4 carrying any desired conducting member, such, for example, as an anode stem 5. The insulating bushing 4 is provided with an exterior flange 18 having an upper plane surface 9 and a lower plane surface 19. The surface 19 is seated on the upper surface of a flange 6 on the cover. In order that the insulating bushing 4 may be accurately centered in the opening in the cover, the latter is provided with an inwardly extending member 11 adapted to bear against the lower portion of the bushing. A peripheral flange 6 surrounds the opening in the cover and is exteriorly threaded to engage with an interiorly threaded collar 7. An exteriorly threaded ring 8 engages the collar 7 and bears upon the flat shoulder 9 of the insulating bushing 4, allowance being made for expansion and

contraction by a compressible gasket 10 of some refractory fibrous material, such, for example, as asbestos.

The bushing 4 is also provided with an inferior flange 12 having plane upper and lower bearing surfaces 13 and 13^a. The anode stem 5 is provided with a shoulder 17 having a plane upper surface 13 adapted to bear against the lower face of the flange 12. The anode stem 5 is threaded, as shown at 14, and an interiorly threaded sleeve 15 engages therewith and bears upon the upper surface of the flange 12, through a compressible gasket 16 of asbestos or similar material. The anode stem 5 is accurately centered in the bushing 4 by engagement therewith at the point 17. After the seal is assembled, as above described, spaces 20, 21, 22, 23, 24, 25 and 31 may be filled with any suitable sealing liquid, such, for example, as mercury, and, if the device is to be mounted upon a moving vehicle, such as a railway locomotive, the sealing liquid may be retained in place by wax or other suitable means.

The flange 18 is forced to withstand the pressure of the clamping device provided between bushing 4 and cover 3 and the flange 12 is obliged to withstand the pressure of the clamping device between the bushing 4 and anode stem 5. Very heavy strains are accordingly exerted upon the comparatively small section of vitreous material connecting these two flanges, frequently causing fracture at this point. I have obviated this difficulty by making the interior and the exterior flanges of the insulating bushing 4 of considerable thickness, as shown at 26 and 27 in Fig. 2. These flanges are so placed as to overlap to a marked degree, thus providing a large cross section of the vitreous material at the point of maximum strain. Flanges 26 and 27 are under-cut, as shown at 28, in order that the strain shall be uniformly distributed upon the bearing surfaces 29 and 30.

I am aware that it is old to clamp an anode stem into the cover of a metallic containing receptacle, as shown for example in United States patent to Sakai No. 1,049,404; but, in all seals of this character that have

been brought to my attention, the bearing surfaces between the bushing and the cover and between the stem and the bushing have been conical in shape. It is extremely difficult, under such conditions, to obtain an accurate fit between the two bearing surfaces, since a different mechanism must be employed to machine each type of surface, and all such mechanism must be set at a definite 5 adjusted angle. My improved seal has plane bearing surfaces throughout, a plane surface being the easiest type to machine with accuracy. Seals of the Sakai type must be ground together, as is the ordinary 10 practice with the valves of automobile engines, and while, by this means, a close fit may be obtained in each particular case, yet the elements of such seals are not interchangeable. In my seal, the bearing 15 surfaces being perfectly plane, absolute interchangeability is inherent.

In the manufacture of a forged steel cover, such as 3, it is extremely difficult to entirely free the metal from internal stress. The result of this is that, when the cover is heated in the operation of the rectifier, it expands much more along a certain diameter than it does in other directions. This unequal expansion causes what was previously a circular 20 seat to become slightly elliptical and hence causes an unavoidable leak in a conical seal but has no effect whatsoever upon my seal.

The tendency of the clamping elements in a seal of the Sakai type is to burst the insulating bushing. Vitreous material, such as porcelain, is ill adapted to withstand a bursting strain, owing to its low tensile strength. I eliminate all bursting strains and use the material of the insulating bushing 35 entirely in compression.

While I have described the anode stem, the insulating bushing, and the opening in the cover of the containing receptacle all as being circular in shape, it will be understood 40 that they may be made elliptical, square, or of any other desired shape. I shall accord-

ingly use the term "peripheral" in referring to the relative location of these parts.

Having thus described my invention what I claim is:

1. The combination with a plate of conducting material provided with an opening, of an insulating bushing provided with peripheral flanges on its interior and its exterior surfaces, respectively, said bushing being seated in the opening and having its exterior flange engaging the plate in a plane bearing surface, an interiorly threaded collar engaging a peripheral flange on the plate and surrounding the insulating bushing, an exteriorly threaded ring engaging the collar and bearing upon the exterior flange of the bushing, a conducting member provided with a peripheral flange projecting through the bushing, said peripheral flange engaging the interior flange of the bushing in a plane bearing surface, and means for clamping the conducting member to the insulating bearing.

2. The combination with a plate of conducting material provided with an opening therethrough and having an annular groove surrounding said opening, of an insulating bushing provided with a peripheral flange on its exterior surface, said bushing being seated in said opening and having one face of said flange engaging said plate, a collar surrounding said bushing and in threaded engagement with a wall of said groove, a clamping member surrounding said bushing in threaded engagement with said collar and bearing upon the opposite face of said flange, whereby said bushing is clamped to said plate, and a conducting member extending through said bushing.

In testimony whereof, I have hereunto subscribed my name this 27th day of April, 1914.

FRANK CONRAD.
